WALTHER AKEMANN, OF ESSEN, GERMANY, ASSIGNOR TO FRIED. KRUPP AKTIEN-
GESELLSCHAFT, OF ESSEN-ON-THE-RUHR, GERMANY.

ELECTRICAL SWITCH.

Application filed September 8, 1920. Serial No. 408,068.

To all whom it may concern:

Be it known that I, Dr. WALTHER AKEMANN, residing at Essen, Germany, a citizen of the German Republic, have invented a 5 certain new and useful Improvement in Electrical Switches, of which the following is a specification.

This invention refers to an electrical switch, which is operated by compressed air 10 produced by the mouth of the man operating the switch, or to a so-called mouth operated switch and it has for its object to create an electrical switch of this kind the organ of which, exposed to the compressed 15 air current, possesses a particularly easy motion and moreover is easily interchangeable and adapted to be disassembled in a very simple way. This object is attained according to the invention by arranging a 20 piston within a cylinder which is detachably connected to the switch casing, so that the piston and cylinder may be removed independently of the movable part of the switch proper which part cooperates with the piston 25 ton.

The invention will be described with reference to a switch intended for bridging over a bipolar gap in an electrical circuit which is shown in the accompanying drawings in which—

Figure 1 is a vertical section through the casing of the switch and

Figure 2 is a section on the line 2—2 of Figure 1 looking from above.

The interior of the substantially cylindrical casing A of the switch is closed in by a cover B (see Figure 2) placed on the front of the casing and adapted to be attached thereto by means of screws, a packing 35 ring b¹ being placed between it and the casing. On its underside the casing A has a cylindrical flange a¹ (see Figure 1) to which is attached by means of screws a downwardly extending socket C and a packing 40 ring is inserted between the two.

In the socket C is guided an easily movable hollow cylindrical piston D, the edge of the piston face of which is supported on an annular shoulder on a nozzle c¹ 45 screwed watertight to the socket C and which nozzle serves for the attachment of the air pipe (not shown). The piston D has a short upwardly extending piston rod d¹, upon the upper end face of which bears 50 a bolt E forming a force-closing element.

a², a³ is a bracket-shaped holder whose vertical limb a³ is screwed to the rear wall of the casing A and whose horizontal limb a² is vertically bored to receive the longitudinally movable bolt E which is acted on by 60 a spring F, which spring F bears with one end against the limb a² and with its other end against a flanged disc e¹ and tends to thrust the bolt E downwards.

The upper end of the bolt E which projects from the limb a² is provided with a collar e², which limits the downwardly directed movement of the bolt E and serves as a support for a transverse carrier e³ of 65 non-conducting material pushed over the upper end of the bolt E. This transverse carrier e³ is prevented from being lifted off by a screw in the well-known manner shown in the drawing.

Upon the ends of the transverse carrier e³ are mounted two stirrups e⁴ composed of conducting material and rigidly connected thereto by screws e⁶ (see Figure 2) and the ends of which are bent up elastically 70 in the manner shown in Figure 1 and carry 75 the contacts proper e⁵ of the movable part of the switch.

The fixed part of the switch is formed by four screw clamping bolts G intended for the attachment of the conductors H and mounted on a terminal plate a⁵ of non-conducting material screwed to two lugs a⁴ on the limb a³. The heads g¹ of the bolts G which project from the underside of the 80 terminal plate a⁵ form a bipolar gap in the 85 circuit which can be bridged over by the two elastic stirrups e⁴. The conductors H are passed through a socket a⁶ cast on the wall of the casing.

When a current of air impinges on the end face of the piston D, it rises and pushes with its piston rod d¹ the bolt E of the movable part of the switch the spring F being compressed. At the same time the elastic 90 stirrups e⁴ bear with their contacts e⁵ against the heads g¹ of the terminal screw bolts G and thus bridge over the gap in the circuit. When the current of air ceases the bolt E, the contacts e⁵ rigidly connected thereto and the piston D return under the action of their 95 own weight and that of the expanding spring F to the position of rest shown in the drawing, whereby the circuit is again broken.

The fact that the member which is ex- 100 105 110

posed to the action of the current of air and operates the movable part of the switch, is mounted in a socket which is connected in an easily detachable manner to the casing of the switch, while on the other hand the movable part of the switch is mounted in the casing itself of the switch, affords a particularly advantageously constituted general arrangement of the switch, as firstly 10 the member which is exposed to the directly applied action of the current of air (viz, the piston D) is conveniently accessible and easily interchangeable, as it can be removed from the casing A of the switch together 15 with the socket C, and secondly the movable part of the switch (E to e⁶) which forms the one sensitive part of the switch is so mounted in the casing A of the switch that even after the removal of the socket 20 C it does not project from the casing A and is therefore protected from injury.

Claims:

1. A mouth operated electric switch comprising a casing, fixed and movable switch 25 contacting means within said casing, said movable contacting means being carried on a plunger reciprocably mounted in said casing, a spring tending to hold said movable contact means in spaced relation to said 30 fixed contacting means, a cylinder attached to said casing in substantially axial alinement with said plunger, a piston in said cylinder and projecting in said casing through an aperture provided in the latter 35 whereby said piston abuts said plunger, and a mouth-piece on said cylinder whereby air

being blown into said mouth-piece said movable contacting means is urged against said fixed contacting mean; said mouth-piece, cylinder and piston being detachable as a unit from said casing, and said plunger being so disposed as to lie entirely within said casing when said detachable unit is removed. 40

2. A mouth operated electric switch comprising a casing, fixed contact points and a bridge for cooperation therewith in said casing, said bridge being carried on a plunger reciprocably mounted in said casing, a spring acting on said plunger for normally 45 holding said bridge away from said fixed contact points, a cylinder attached to said casing in substantially axial alinement with said plunger, a piston in said cylinder and projecting through said casing through an 50 aperture provided in the latter whereby said piston abuts said plunger, and a mouth-piece on said cylinder whereby air being blown into said mouth-piece said bridge is urged against said fixed contact points; said 55 mouth-piece, cylinder and piston being detachable as a unit from said casing, and said plunger being so disposed as to lie entirely within said casing when said detachable unit is removed. 60

The foregoing specification signed at 65
Essen, Germany, this 18th day of May, 1920.

DR. WALTHER AKEMANN.

In presence of—

HANS GOTTMANN,
JOSEF OLCERTZ.
